UNITED STATES PATENT OFFICE.

ANDREW M. STEWART, OF TOLEDO, OHIO, ASSIGNOR TO THE NATIONAL SUPPLY COMPANY, OF TOLEDO, OHIO, A CORPORATION OF OHIO.

WELL DRILLING AND PUMPING TEMPER-SCREW.

1,180,617.

Specification of Letters Patent. Patented Apr. 25, 1916.

Application filed November 16, 1914. Serial No. 872,310.

To all whom it may concern:

Be it known that I, ANDREW M. STEWART, a citizen of the United States, residing at Toledo, in the county of Lucas and State of Ohio, have invented new and useful Improvements in Well Drilling and Pumping Temper-Screws, of which the following is a specification.

My invention relates to temper screws for well drilling and pumping apparatus.

The object of my invention is broadly to provide an improved connection between the walking-beam or equivalent device of a drilling rig and the drilling or pumping tools.

More specifically it is the object of my invention to construct such a connection, called a temper screw with detachable or renewable parts so that, when a part is broken or worn out, it may be renewed without providing a new temper screw or even an expensive part thereof.

My invention will be more fully understood in connection with the accompanying drawings, in which—

Figure 1 is a side view, partly broken away, of a temper screw constructed in accordance with the principles of my invention and accompanied with portions of a walking beam and a drill or pump cable; Fig. 2, an elevation looking at Fig. 1 toward the left; Fig. 3, a section just below the part marked 14 on Fig. 1; Fig. 4, a section on the line IV—IV, Fig. 1; Fig. 5, an elevation showing a modification of the upper end of the T; and Fig. 6, a side elevation of a second modification of Fig. 1, parts being broken away.

On Figs. 1 to 4, 1 represents a walking-beam having the open-ended slot 2, in which the vertical parallel side-bars 3 are suspended by means of the cross-bar 4 supported in depressions or otherwise on the top of the walking-beam. The cross-bar 4 is clamped between the two clamp-members

5 and 6, through both of which the upper ends of the side bars pass, the members being drawn tightly into engagement with the cross-bar by the nuts 7 working on the side-bars and against the clamping members. Heretofore, it has been common to make the bars 3 and the cross-bar 4 in a single piece called a T.

In Fig. 5, I have shown the T constructed as follows: The cross-bar and the clamping

members of Figs. 1 to 4 have been made of a single piece of metal, comprising the block 8 having the two lateral projections or trunnions, which rest on the walking beam the same as the ends of the cross-bar 4. In Figs. 1 to 4 the cross-bar is separate from the means for supporting the side-bars, while in Fig. 5, it is integral with the said means. The side bars both extend through the block and are connected thereto by the nuts 10 working on the side-bars and engaging the upper and lower surfaces of the block.

In Figs. 1 to 4, I show the lower ends of the side-bars screwed into respective sectional or half-nuts 11 and provided with the nuts 12 in engagement with the half-nuts. These half-nuts need not carry threaded linings, inasmuch as the half-nuts may be readily exchanged for fresh ones and their cost is slight. Heretofore the sectional nuts have been made integral with the side-bars, which required a new pair of side-bars when either section or half of the nuts needed replacement. However, as the side bars were integral with the cross-bar as well as with the half-nuts, a breakage or other defect of any part of the integral structure, required a replacement of the entire structure.

The main screw 13 works in the said half-nuts which are drawn toward each other and into threaded engagement with the screw by means of the yoke 14 having one end member in engagement with the outer face of one half-nut, the other end member of the yoke being provided with the T-screw 15 with its inner end in engagement with the outer face of the other half-nut. The lower end of the screw is swiveled in the horizontal bar 16, on the ends of which the links 17 are suspended. The screw is provided with the cross-handle 18 by which it may be rotated.

18^a is the usual cross-bar on the top of the screw 13.

To the lower end of each link 17, I suspend the eye-bolts or rods 19 threaded at their lower ends. These eye-bolts extend down through the respective clamp-members 20 between which the cable or rope 21 is clamped by means of a second yoke 22 and T-screw 23. The members 20 are preferably secured on the rods 19 and the nuts 24 are screwed up against the bottoms of the clamp-members.

100

105

110

In Fig. 6, the side rods support the clamp-members 20 directly, the nuts 24 being screwed on the side-bars instead of on the eye-bolts. The clamp-members are connected to the side-bars in the same manner that the half-nuts 11 are on Figs. 1 and 2. It has been the usual practice to make each of the clamp-members integral with the means for suspending them on the links 17. 10 By my improvement, if one clamp-member or one eye-bolt needs replacing, it is only necessary to replace a part thereof.

I claim—

1. In a well pumping and drilling apparatus, a reciprocating member and a temper screw, the latter containing a pair of clamp-members, vertical bars extending through the clamp-members, and a horizontal cross-bar clamped between the clamp-members 15 and bearing on the reciprocating member.
2. In a well pumping and drilling apparatus, a reciprocating member having a forked end, a pair of trunnions supported by the members of the fork, a block supporting the trunnions, a pair of vertical side-bars extending through the block at opposite sides of the trunnions, and means for removably securing the side-bars to the block and in fixed relation thereto. 25
3. In a well pumping or drilling apparatus, a reciprocating member, a pair of vertical side-bars suspended on the same, sectional nuts each having an opening to receive one of the side bars, means for detachably connecting each sectional nut to the side bar therein, a vertical screw coöperating with the sectional nuts, and means for releasably holding the sections of the nut in coöperative relation with the screw. 30
4. In a well pumping or drilling apparatus, a temper-screw having a pair of side bars, sectional nuts having holes in which the lower ends of the bars are removably seated, a screw, and means for releasably holding the sectional nuts in threaded connection with the screw. 40
5. In a well pumping or drilling apparatus, a vertically-reciprocating member, side-bars threaded at both ends, a horizontal cross-bar bearing on the reciprocating member, a support for the cross-bar, means for detachably connecting the upper ends of the 45

side-bars to the said support, half-nuts through which the lower ends of the side-bars extend, for detachably connecting the 55 half-nuts to the side-bars, a vertical screw between the half-nuts, and means for holding the half-nuts in engagement with the screw.

6. In a well pumping or drilling apparatus, a vertically-reciprocating member, side-bars threaded at both ends, a horizontal cross-bar bearing on the reciprocating member, a support for the cross-bar, means for detachably connecting the upper ends of the 60 side-bars to the said support, half-nuts through which the lower ends of the side-bars extend, provided with means for detachably connecting the half-nuts to side-bars, nuts on the side-bars for locking the 70 half-nuts and side-bars in rigid relation to each other.

7. In a well pumping or drilling apparatus, a reciprocating member, a pair of vertical side-bars suspended thereon, a vertical 75 member extending downwardly between the lower ends of the side-bars, separate and distinct devices through which the lower ends of the side-bars extend, and which are removably secured thereto, the said devices 80 being arranged to engage opposite portions of the said vertical members, and means for causing the said devices to releasably hold the said vertical member between them.

8. In a well pumping or drilling apparatus, a vertically reciprocating member, a vertical screw, side-bars threaded at both ends, a horizontal cross-bar bearing on the reciprocating member, a support for the cross-bar, nuts on the side bars for detachably 85 securing the support to the upper ends of the side-bars, half-nuts provided with means for detachably connecting the half-nuts to the lower ends of the side-bars, nuts on the side-bars for detachably locking the half- 90 nuts in position, and means for holding the half-nuts in engagement with the screw. 95

Signed at Toledo, Ohio, this 10th day of November A. D. 1914.

ANDREW M. STEWART.
